UNITED STATES PATENT OFFICE.

CHARLES DANIELSON, OF MINNEAPOLIS, MINNESOTA.

IRONING BOARD.

Application filed May 17, 1921. Serial No. 470,288.

To all whom it may concern:

Be it known that I, CHARLES DANIELSON, a citizen of the United States, residing at Minneapolis, in the county of Hennepin and 5 State of Minnesota, have invented certain new and useful Improvements in Ironing Boards; and I do hereby declare the following to be a full, clear, and exact description of the invention, such as will enable others 10 skilled in the art to which it appertains to make and use the same.

My invention relates to ironing boards, of the collapsible or folding type, and has for its object to improve the construction and 15 action thereof.

It is a well known fact that a more stable and better support for an ironing board can be had with four legs than with three legs, providing all four legs have firm contact 20 with the floor. However, floors are very frequently, and in fact, usually, more or less irregular, so that one of the legs will not have contact with the floor, and hence, will fail as a support, leaving the board supported by three legs, not at all well disposed 25 for that purpose.

To avoid the above trouble, many, or at least some boards have been provided with but three supporting legs with the one leg 30 centrally located; and this gives a fairly good support, but not nearly as good as will be afforded by four legs, properly disposed and properly engaged with the floor.

My invention provides extremely simple 35 and efficient means for quick adjustment to positively insure firm engagement of all four legs of the board with a floor, regardless of irregularities or unevenness in the latter, and thereby rigidly support the ironing board 40 so that it will not wiggle, wobble, collapse or move on the floor when ironing.

To the above ends, generally stated, the invention consists of the novel devices and combinations of devices hereinafter described and defined in the claims.

In the accompanying drawings, which illustrate the invention, like characters indicate like parts throughout the several views.

Referring to the drawings:—

50 Fig. 1 is a perspective view of the improved ironing board;

Fig. 2 is a view partly in elevation and partly in vertical section; and

55 Fig. 3 is a fragmentary view of the supporting frame, as shown in Fig. 2 and adjusted to an uneven floor.

The numeral 4 indicates an ironing board with the customary tapered end and having rigidly secured to the under side, transverse cleats 5 and 6, the former of which is at the wide end thereof, and the latter of which is at the intermediate portion thereof. On the ends of the cleats 5 and 6, are trunnions 7 and 8, respectively. The frame for the ironing board 4 includes a pair of relatively short upright legs 9, a pair of relatively long oblique legs 10, and a pair of short legs 11, pivoted on the trunnions 8 and which legs 11 form a part of a bracket as will presently appear.

The pairs of legs 9 and 10 are pivoted on the trunnions 7, the latter within the former, and the legs 9 are rigidly connected at their upper ends, by a transverse tie-bar 12. This tie bar 12, in addition to rigidly connecting 75 the legs 9, holds the same on the trunnions 7 and said legs 9, in turn, hold the legs 10 on said trunnions against the ends of the cleats 5. The legs 9 are further rigidly connected below the tie-bar 12 by crossed tie-bars 13, 80 and which tie-bars and the tie bar 12 are, preferably, in the form of metal straps of sufficient thickness to prevent bending. The legs 10 are rigidly connected at their lower intermediate portions by rungs 14, and extend obliquely from cleat 5 to a point where they engage the floor which is well under the tapered end of the ironing board.

To hold the pairs of legs 9 and 10 from moving on the trunnions 7 and also hold the same in different oblique positions in respect to themselves, to support the wide end of the ironing board at different elevations, said pairs of legs are adjustably connected by a yoke-like metallic tie-strap 15 which 95 embraces the pairs of legs 10, and its arms are pivoted, one to each of the legs 9 for vertical swinging movement. The intermediate portion of the tie-strap 15 is arranged to enter either of two longitudinally spaced sets of lock notches 16, arranged in aligned pairs and formed in the upper edges of the legs 10. To give additional stability to the ironing board frame the legs are outwardly inclined in respect to the oblique 100 legs 10, and the legs of each pair are spread at their lower ends.

The leg bracket, heretofore referred to, in addition to the legs 11, includes an upper tie-bar 17 and a lower combined tie-bar and 110 lock blade 18. The tie bar 17, not only rigidly connects the legs, but holds the same on

the trunnions 8 and the combined tie-bar and lock bar 18 extends outward of the legs 11 for engagement with either of two longitudinally spaced sets of lock notches 19 arranged in aligned pairs and formed in the upper edges of the pairs of legs 10, considerably below the lock notches 16. The combined tie-bar and lock blade 18 is secured to the legs 11 for angular adjustment in a vertical plane by forming therein, vertical slots 20 through which project thumb nuts equipped bolts 21, anchored in the legs 11. By tightening the thumb nuts on the bolts 21, the combined tie-bar and lock blade 18 may be frictionally clamped to the legs 11 in different adjustments.

Pivoted to the under side of the ironing board 4, at the tapered end thereof, is a sleeve board 22 for movement from an inoperative position completely under the ironing board to an operative position in which it projects from under the ironing board, at one edge thereof, and is firmly held in this position by the bracket 23, secured to the ironing board.

When the improved ironing board is folded, the pair of legs 10 extend within the pair of legs 9 and the pair of legs 11 extend within the pair of legs 10, and all of the legs, together with said leg bracket are substantially parallel to the ironing board.

To set up the improved ironing board, the same may be supported on its tapered end and the two pairs of legs 9 and 10 spread and connected by the yoke-like tie-strap 15 so as to support the wide end of the ironing board at the desired height. The leg bracket is then turned away from the ironing board and its combined tie-bar and lock blade 18 interlock with one of the sets of lock notches 19 to adjust the tapered end of the ironing board to the same height as the other end thereof.

In case the floor is uneven and all four legs 9, and 10 do not firmly rest thereon, the ironing board may be held with three of its legs 9 and 10 on the floor, to wit, both legs 9 and one of the legs 10. One end of the combined tie-bar and lock blade 18 may

then be released by loosening one of the nuts of one of the bolts 21 and said combined tie-bar and lock blade angularly adjusted to force the raised leg 10 into contact with the floor, provided it is not sufficiently loose to drop, of its own weight. The loosened thumb nut may then be tightened with both ends of the combined tie-bar and lock blade 18 firmly seated in one of the sets of the lock notches 19 and with both of the legs 10 on the floor.

The above described invention has, in actual usage proven highly efficient for the purpose had in view.

What I claim is:

1. An ironing board having four legs pivoted in pairs at the same end of the ironing board, one pair of said legs being extended obliquely under the ironing board, and a leg bracket pivoted to the ironing board and having an angularly adjustable blade engaged with said obliquely extended legs.

2. An ironing board having four legs pivoted in pairs at the same end of the ironing board, one pair of said legs being extended obliquely under the ironing board and having longitudinally spaced lock notches, means adjustably connecting said two pairs of legs, and a leg bracket pivoted to the ironing board and having an angularly adjustable blade engageable with said lock notches.

3. An ironing board having four legs pivoted in pairs at the same end of the ironing board, one pair of said legs being extended obliquely under the ironing board and having longitudinally spaced lock notches, a yoke-like tie-strap having its arms pivoted to the other pair of said legs, embracing said obliquely extended legs with its transverse portion arranged for interlocking engagement with certain of said lock notches, and a leg bracket pivoted to the ironing board and having an angularly adjustable blade for interlocking engagement with certain of said lock notches.

In testimony whereof I affix my signature.

CHARLES DANIELSON.
